MEANS FOR TUNING SHORT-WAVE HOLLOW-BODY RESONATOR APPARATUS

Alden H. Ryan, Wilkinsburg, Pa., assignor to Westinghouse Electric & Manufacturing Company, East Pittsburgh, Pa., a corporation of Pennsylvania

Application August 13, 1940, Serial No. 352,412

4 Claims. (Cl. 250—27.5)

My invention relates to high-frequency or short-wave electrical apparatus, and it has particular relation to such apparatus utilizing conductor-ensheathed hollow-body resonators, operating at wave lengths of the order of 40 centimeters, or between the limits of one centimeter and five meters, more or less. Still more particularly, my invention relates to novel means for tuning the same.

The resonant frequency of a hollow-body resonator depends upon its shape, its physical dimensions, and the mode or manner of its oscillation. Tuning of such hollow-body resonators may be effected by means of putting large accordion-pleated, expandible and contractable, thin-walled metal annular members in a portion of the cylindrical wall of a cylindrically shaped resonator, for changing the axial length of the cylinder.

In accordance with my invention, the aforesaid method of tuning is utilized in an electronic device in which an electron-beam is passed axially through two such cylindrically shaped resonators, disposed back-to-back, with a shorter cylindrical member disposed inside of the same, so that the electron-stream is first velocity-modulated as it passes through an opening in the end-wall of the first resonator, and then through the first end of the inner cylinder, the electrons of the velocity-modulated stream becoming bunched in their transit through the inner cylinder, and finally giving up some of their energy as they pass out of the second end of the inner cylinder and through an opening in the end-wall of the second resonator.

An object of my present invention is to avoid difficulties which have been experienced in moving the end walls of the resonators toward and away from the respective ends of the inner cylinder, which has resulted in a change in the transit-time required for the passage of the electrons through the intervening portions of the respective resonators, thus lowering the efficiency of the apparatus. The aforesaid tuning-method has also involved a disadvantage because of the large size of the flexible-wall portion which was needed in order to effect the change in longitudinal dimension, making it difficult to maintain a vacuum in the device or to outgas the device, when it is being originally assembled, without overheating the thin wall-parts in the process.

It is a further object of my invention to provide means for changing the tuning of such resonators without disturbing either end-wall, and

without requiring large-size flexible-wall members for effecting the tuning.

It is also an object of my invention to provide a high-frequency hollow-body resonator having a re-entrant wall-portion defining a restricted space-portion between two relatively closely spaced wall-portions, as compared to other dimensions of the resonating-space, in a combination utilizing an externally controllable movable means for changing the effective capacity between said two relatively closely spaced wall-portions, as a means for tuning the resonator, and in combination, also, with coupling-circuit means for coupling the internal oscillations within said resonator to some external device.

Another object of my invention is to provide means such as that just described, in an electron-tube device in which an electron-beam is modulated and controlled with the aid of a tunable resonator of the type just described.

With the foregoing and other objects in view, my invention consists in the apparatus, structures, combinations, systems and methods hereinafter described and claimed, and illustrated in the accompanying drawing, wherein:

Figure 1 is a diagrammatic horizontal sectional view of an exemplary form of embodiment of apparatus embodying my invention, with a diagrammatic representation of external circuits and apparatus for utilizing the same; and

Fig. 2 is a vertical sectional view on the plane indicated by the line II—II in Fig. 1.

The form of embodiment of my invention as illustrated in the drawing consists of an evacuated metal container comprising an elongated cylindrical wall-portion 4 and two hermetically joined end-wall portions 5 and 6, respectively. Disposed within the cylinder 4 is a centrally disposed metal partition-wall 7 which is in turn provided with a central opening 8 in which is secured a smaller metal cylinder 9 having open ends 11 and 12, respectively. Disposed between the inner cylinder end 11 and the first end-wall 5 of the outer cylinder, is a metal partition-member 13 which is provided with a central opening 14 in alignment with, and closely spaced from, the end-opening 11 of the inner cylinder 9. A similar metal partition-wall 15 is provided at the other end of the device, between the inner-cylinder end 12 and the end-wall 6 of the outer cylinder, said partition-wall 15 being provided with a central opening 16 in alignment with, and closely spaced from, the end opening 12 of the inner cylinder 9. The intervening space between the two openings 14 and 11 constitutes a part of a

larger resonating-space 18 which extends between the two cylinders 4 and 9 and between the two partitions 13 and 7. In like manner, the intervening space between the two openings 12 and 16 constitutes a part of a second resonating-space 19 which extends between the two cylinders 4 and 9 and between the two partitions 7 and 15.

In the illustrated form of the invention, means are provided for producing an electron-beam which passes successively through the central openings 14, 11, 12 and 16. The beam-producing means includes a source of emitting electrons which is illustrated as a filament 21 disposed in the space between the end-wall 5 and the first partition 13. Said filament 21 is provided with terminal-leads 22 and 23 which extend out of the casing through vacuum-tight insulating bushings 24 disposed in the end-wall 5. In order to make it possible to maintain the suitable electron-stream within the container, the container 4—5—6 is evacuated to a suitable degree, such as a vacuum of the order of 10^{-6} millimeters of mercury, or any other suitable amount depending upon the current and voltage ratings of the device and the sharpness of focusing of the electron-beam, which is required or desired.

The electrons emitted from the filament 21 are focused into a beam as they pass through the first partition-opening 14, or any more elaborate focusing-means may be utilized, as is well known in the art of electronic apparatus. The electrons in this portion of the beam are also accelerated by means of a voltage-difference which is supplied by means of an adjustable battery 25, which is connected between a grounded point 26 of the outer casing, and one of the leads 23 of the filament 21. In passing through the first intervening space between the first two central openings 14 and 11, the electron-beam is subjected to the velocity-modulating influence of the electrostatic field-portion of the oscillations within the first resonating space 18. The velocity-modulated electron-beam then passes into a second intermediate space between the opposite end-openings 11 and 12 of the inner cylinder 9, thus providing what is known as a drift-space in which velocity-modulated electrons may have an opportunity to become bunched, so that the first resonating space 18 is commonly known as a buncher.

The bunched electrons emerge from the third central opening 12 into the intermediate space between the third and fourth openings 12 and 16, which space is a part of the second resonating space 19, which is commonly known as a catcher, because it absorbs some of the energy of the bunched electrons, the successive bunches or impulses of electrons occurring at a high-frequency rate corresponding to the resonant frequency of the catcher 19, so as to increase the internal oscillations therein.

The electron stream finally leaves the last opening 16 and enters the last compartment of the device, between the partition 15 and the end-wall 6, where the electrons are finally dissipated or collected on the walls of said space. An electron beam deflector is shown, in the form of a floating or insulatedly mounted electrode 30 of carbon or other material having a secondary electron-emissivity ratio materially less than unity, as is described and claimed more particularly in a copending application of G. L. Tawney, Serial No. 323,935, filed March 14, 1940, and

assigned to the Westinghouse Electric & Manufacturing Company.

The illustrated apparatus also includes an external-circuit exciting-device for exciting the internal oscillations of the first resonator-space 18 from some source outside of said space, said means being illustrated in the form of a feedback means from the catcher resonator-space 19. The feedback means is illustrated as a magnetic coupling device including half-loop 31 and 32 terminating on opposite sides of the central partition 7 and including an intermediate conductor 33 joining said loops, said conductor 33 passing, in spaced relation, through a suitable opening 34 in the central partition 7.

In accordance with a preferred form of embodiment of my present invention, I provide a tuning means in the form of means for in effect changing the capacitance between the spaced wall-portions containing the openings 14 and 11, and between the spaced wall-portions containing the openings 12 and 16. To this end, externally controllable movable means must be provided, associated with the intervening spaces in question. A preferred means for effecting such a control, as illustrated, comprises a narrow auxiliary electrode 35 and 36, one for each of the intervening spaces to be controlled, each of said auxiliary electrodes, such as the electrode 36, being movable in and out, through a slotted opening 37 in the outer cylindrical wall 4. Disposed outside of the cylindrical casing-wall 4, so as to cover the elongated slot 37, is a hermetically joined flexible-walled protuberance 38, which has thin flexible metal walls pleated like an accordion, so that the end 39 of the protuberance can be moved in and out, toward and away from the cylindrical housing-member 4. The outer end of the movable electrode 36 is hermetically joined to the end-wall portion 39 of this flexible protuberance 38, and an extension 40 of said movable electrode 36 is disposed on the outside of the protuberance 38 for the purpose of securing an external control of the position of the auxiliary electrode 36. In the form of my device which is illustrated, the extension 40 is intermediately pivoted to a lever 41 which is pivoted, at one end, to a lug 43 on the cylindrical enclosure-member 4, and which is adjustable, at the other end, toward and away from the cylindrical enclosure 4, by means of a set screw 44 which may be mounted in a bracket 45.

In operation, the movable tuning electrode 36 is disposed in the space between the partition 15 and the end 12 of the inner cylinder 9, and said movable tuning electrode 36 extends down to the vicinity of the longitudinally extending line joining the edges of the openings 12 and 16, so that it extends to the vicinity of the edge-portion of the electron-beam. The tuning electrode 36 is electrically connected to an extension of the wall-portion or partition 15 which is provided with the opening 16, so that, as the movable tuning electrode 36 is moved in and out, it changes the electrostatic coupling with the end of the inner cylinder 9. The effect of this change is to strongly change the resonance-frequency of the "catcher" resonator-space 19. In a similar manner, the other movable tuning electrode 35 controls the tuning of the "buncher" resonator-space 18.

When the filament 21 is heated, and when a suitable voltage, from 500 volts to 5,000 volts, is applied thereto for the purpose of accelerating the electrons, an electron beam is established

which is modulated in the first intervening space between the openings 14 and 11 of the buncher 18, and which gives up some of the energy of the bunched electrons in the "catcher" intervening space between the openings 12 and 16. Some of the oscillation-energy of the catcher 19 is taken off, in a coupled output-circuit which is illustrated as comprising a half-loop 47 terminating on the inside of the partition 15, within the second resonating-space 19, and having a terminal conductor-portion 48 which extends out through an opening 49 in the partition 15, and which is connected to an external conductor 51 which extends out of the casing, through a vacuum-sealed insulating bushing 52, and is connected to some external apparatus utilizing the high-frequency energy, such as an antenna 53.

My novel tuning-electrodes 35 and 36 make it possible to quickly and minutely control the output-frequency, even while the device is in operation.

In the illustrated form of embodiment of my invention, the four central openings 14, 11, 12 and 16 are covered or closed with grids 54, 55, 56 and 57, respectively, said grids being illustrated symbolically as metal-wire screens, although such illustration is intended to be symbolic of any open-work grid-construction which is known in the art of electron-tube control. I desire that the terms opening and grid shall be construed to be synonymous with each other, and interchangeable, either one designating either a single opening or a plurality of juxtaposed openings.

While I have described my invention in a single preferred form of embodiment, I desire it to be understood that said form of embodiment is only illustrative, and that various changes may be made in the precise details of construction and arrangement, without departing from the essential idea of the invention, at least in its broader aspects. I desire, therefore, that the appended claims shall be accorded the broadest construction consistent with their language.

I claim as my invention:

1. An electron-discharge apparatus comprising an evacuated container; means therein for producing an electron-beam; a modulating beam-coupling means for operating on said electron-beam at one region thereof for modulating said beam at a predetermined high-frequency rate; an excitable beam-coupling means to be acted upon by said electron-beam at another region thereof for absorbing high-frequency energy from the modulations of said beam; said beam-coupling means including hollow-body resonator-means to be excited to oscillate at a common resonating-frequency and including frequency-changing means for adjusting said common resonating frequency, said frequency-changing means including an externally controllable movable means adjacent to the path of said beam for varying the capacity-effects in its vicinity without changing the effective extents of said beam-coupling means along the path of said beam; coupling excitation-means mounted in said hollow-body resonator-means for supplying high-frequency excitation-energy to said modulating beam-coupling means; and coupling output-means mounted in said hollow-body resonator-means for deriving high-frequency electrical energy from said excitable beam-coupling means.

2. An electron-discharge apparatus comprising an evacuated container; means therein for pro-

ducing an electron-beam; a first hollow-conductor means for providing a resonator-space, to be traversed by said beam for producing a high-frequency potential-gradient for acting longitudinally upon said beam at a predetermined region thereof; means providing a drift-space to be traversed by said beam after its passage through said predetermined region; and a second hollow-conductor means for providing a resonator-space, to be traversed by said beam issuing from said drift-space, said second hollow-conductor means being adapted to be excited at a resonant-frequency by the high-frequency modulations in said beam and including coupling means coupled thereto for deriving high-frequency electrical energy from the oscillations therein; said two hollow-conductor means having a common resonating-frequency and including frequency-changing means for adjusting said common resonating-frequency, said frequency-changing means including an externally controllable movable means adjacent to the path of said beam for varying the capacity-effects in its vicinity without changing the lengths of the paths to be traversed by the beam in passing through the respective resonator-spaces.

3. A high-frequency resonator comprising an evacuated container; means therein for providing a source of electrons; four successively mounted, spaced grids therein providing a first intervening space between the first and second of said four grids, a second intervening space between the second and third of said four grids, and a third intervening space between the third and fourth of said four grids; an electron-beam-producing means; and hollow-body resonator-means, including said first and third intervening spaces, for utilizing said first and third intervening spaces, in effect, as parts of a buncher and a catcher, respectively, whereby the electrons of said beam are velocity-modulated as a result of the high-frequency resonating electrostatic field in said buncher, and whereby the bunched electrons of said electron-beam yield some of their energy to the high-frequency oscillations within said catcher to supply excitation-energy thereto; said hollow-body resonator-means having a common resonant oscillation-frequency for said buncher and catcher operations, respectively, and including frequency-changing means for adjusting said common resonant oscillation-frequency; said frequency-changing means including an externally controllable movable means in spaced juxtaposition to at least one of said four grids for adjusting the effective capacity between said grid and its associated grid in the hollow-body resonator-means without changing the distance to be traversed by the beam between said grid and its associated grid, whereby the resonating-frequency of said hollow-body resonator-means may be controlled.

4. A high-frequency resonator comprising an evacuated container; means therein for providing a source of electrons; four successively mounted, spaced grids therein providing a first intervening space between the first and second of said four grids, a second intervening space between the second and third of said four grids, and a third intervening space between the third and fourth of said four grids; an electron-beam-producing means; means in said container providing, in effect, at least two separate hollow-body resonators, the first of said hollow-body resonators including said first intervening space within its resonating space for operating as a

buncher for velocity-modulating the electrons of said beam, and the second of said hollow-body resonators including said third intervening space within its resonating space for operating as a catcher for increasing its oscillation as a result of the bunched electrons, most of the space of at least one of said hollow-body resonators including hollow-space dimensions larger than the grid-spacing of its intervening space, said one

5 of the hollow-body resonators also including frequency-changing means including a movable auxiliary conductor-member movably adjustable in the vicinity of said intervening space for tuning the resonator without changing the aforesaid grid-spacing of the associated intervening space, and coupling means for coupling the second one of said resonators to some external device.
